DOLL OR SIMILAR ARTICLE

Lillian de Roche, Eatontown, N. J.

Application July 29, 1955, Serial No. 37,209

Term of patent 14 years

(Cl. D34—4)

The design is characterized by the ornamentation on the body and head elements in relation to the over-all appearance of the doll.

I claim:

The ornamental design for a doll or similar article, substantially as shown and described.
